UNITED STATES PATENT OFFICE

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS

DESIGN FOR A COVER OF A HOUSEHOLD PUMP UNIT

Application filed April 22, 1931. Serial No. 39,593. Term of patent 3½ years.

To all whom it may concern:

Be it known that I, STANLEY H. HOBSON, a citizen of the United States, residing at Rockford, in the county of Winnebago and State of Illinois, have invented a new, original, and ornamental Design for Cover of a Household Pump Unit, of which the following is a specification, reference being had to the accompanying drawing, forming part thereof.

In the drawing—

The figure is a perspective view of a household pump unit cover showing my new design.

The cover has louvers on both sides like the ones appearing in the drawing, and both ends of the cover present substantially the same appearance.

I claim:

The ornamental design for a cover of a household pump unit as shown and described.
